UNITED STATES PATENT OFFICE.

REGINALD STANLEY, OF NUNEATON, COUNTY OF WARWICK, ENGLAND.

BRICK-KILN.

SPECIFICATION forming part of Letters Patent No. 402,628, dated May 7, 1889.

Application filed November 14, 1888. Serial No. 290,773. (No model.)

To all whom it may concern:

Be it known that I, REGINALD STANLEY, a subject of the Queen of Great Britain, residing at Nuneaton, in the county of Warwick, 5 England, have invented new and useful Improvements in Ovens or Kilns for Burning Bricks, Tiles, and other Articles, of which the following is a specification.

My invention relates to improvements in 10 the construction of ovens, kilns, and chambers (which, for the convenience of description, are hereinafter generally referred to as "chambers") for baking or burning bricks, tiles, clay goods, and other material and articles.

My improvements are applicable to muffled chambers, or those in which the heated gases and fire circulate around the chambers but do not come into direct contact, or only partially so, with the contents of the chambers.

In order to enable my invention to be fully understood, I will describe how it can be carried into practice by reference to the accompanying drawings, in which—

25 Figure 1 is a horizontal section of an oven or kiln having muffled chambers for burning bricks, tiles, and other articles, and constructed according to my invention. Fig. 2 is a side or end elevation of one range of 30 chambers, showing the entrances or wickets and fire-doors and the manner in which the chambers are bound together. Fig. 3 is a cross-section of the oven or kiln, the section being taken through the line A A of Fig. 1. 35 Fig. 4 is a cross-section taken through the line B B of Fig. 1. Fig. 5 is a longitudinal section taken through the line D D of Fig. 1.

Similar letters in all the figures indicate 40 similar parts.

In the application of my improvements to this class of ovens or kilns I construct a number of long and narrow chambers, *a a*, arranged parallel with one another and having arched roofs *b b*. In these chambers are placed 45 the goods or materials to be baked or burned, and I have found it advantageous to employ two sets or series of such chambers, as clearly shown in Fig. 1, connected by flues *a' a'*, hereinafter more fully referred to.

50 Between the chambers are formed spaces

or flues *c c*, (which, for the sake of description, I term "lateral flues,") and along which the fire and gases travel or circulate.

a² a² are the outer front and back walls of the kiln.

The side walls, *d d*, of the chambers *a a*, which also form the side walls of the lateral flues *c c*, are constructed of fire-bricks, and are as thin as possible consistent with the strength required to resist the action of the 60 fire and weight of the arches so as to allow the heat to quickly penetrate into and through the contents of the chambers.

At each end of the lateral flues *c*, (or at one 65 end only,) and also in the outer walls, *a²*, I construct fire-holes *e e*, with doors *f f* and bars, in the ordinary manner, to allow of the introduction of fuel, as required, the bars being sanded over and the doors closed tightly when not being fired to prevent the entry of 70 cold air.

Both ends of the parallel chambers can be 75 opened when not being used for burning, for the convenience of drawing and setting, or one end only is left open for that purpose, 80 the other being built up with a double end wall, between which the fire and gases circulate. When set for burning, the open ends of the chambers *a* are closed with double walls or wickets *g h*, Fig. 1, formed by building up the openings *c'*, Fig. 2, with loose bricks and plastering them over, between which walls or covered-up openings the fire passes or circulates, openings *a³ a³* (shown in Fig. 3) 85 being provided for that purpose in the walls *d d*. These openings also allow the fire to pass from one lateral flue *c* to the next. The openings *c'* before being covered up, as described, form the entrances to the chambers *a*, through which the goods or materials to be 90 baked or burned are taken into the said chambers.

At the ends of each of the parallel chambers *a*, between the end walls or wickets, *g h*, are openings *i* in the bottom leading down 95 into underneath flues, *j j*, extending along and under the ends of the parallel chambers *a*, in a direction at right angles to them, into flues *k k*, leading to a chimney, *l*, (or chimneys.) When the openings *i* are not required to be 100

open, they are covered with fire-clay slabs or dampers *m m*, or with other suitable coverings.

Access is obtained to the dampers *m* through a space, *b'*, (shown in Fig. 2,) left in the front wicket, *h*, and made by building a bar of iron in the brick-work, which space is afterward closed by being built and daubed up.

d' d' are dampers for stopping communication between the flues *k k* and the chimney *l*. *e' e'* are dampers for stopping the flues *a'*, serving, when required, to conduct the heated gases from one set of chambers to the other.

In addition to the lateral flues *c*, that convey the bulk of the fire and gases, I construct the top and bottom of the chambers with double walls, so as to form spaces (shown at *n* and *o*, respectively, in Figs. 3 and 4) for the fire and gases to circulate through in communication with the fire and gases in the lateral flues *c*, and which together descend through the openings *i* into the underneath flues, *j*. The fire and gases traversing the double top and bottom are prevented from crossing from one side to the other before they have traveled the length of the chambers *a*. I sometimes, however, make both the arches and bottom of solid brick-work, allowing the heat to radiate from the lateral flues only.

The fire and gases employed to bake or burn the contents of the chambers *a* travel horizontally in the flues *c* around the chambers for the distance required, and are drawn toward the opening or openings *i*, which may be uncovered for that purpose, into the underneath flues, *j*, and from thence into the chimney *l*, up which they ascend and escape into the atmosphere. The draft caused by the chimney makes the fires burn fiercely in the fire-holes *e*, as many of which are fired at one time as may be required. The fire and gases are allowed to escape into the underneath flues, *j*, at one or more of the openings *i* before they reach the last chamber that is being heated. When, however, the number of chambers in the range is small, the fire and gases may be allowed to circulate around all the chambers *a* and escape into the underneath flues, *j*, through the last opening or openings *i*, or that nearest to the chimney *l*.

The fire-holes are successively charged and fired from the farthest from the chimney toward the latter, either one or more chambers being under the hottest fire at once.

Trial-holes *p p*, Fig. 4, are made through the arches, and are also sometimes left through the wickets *g h* of the chambers *a*, and through these holes trials are drawn and the progress of the heating and burning can be watched, and thus regulated. Other holes, *q q*, (shown in dotted lines in Fig. 4,) are left opening into the lateral flues *c*, through which the progress of the firing is inspected and fuel is sometimes dropped.

Holes *r r*, Fig. 3, are left in the inside end walls or wickets toward the chimney, and are

kept open to allow the escape of any steam that may be produced in the process of drying. Small openings are left in the front inside wickets, and sometimes I insert pipes *s* in the outside wickets to allow the entrance of a small current of air, which will assist in carrying off the steam which may be generated during the drying. These holes can be stopped up when the contents have become dry as the burning proceeds, and if the contents and chambers are quite dry at the commencement the holes would of course not be required.

t t, Fig. 2, are iron girders, and *u u* are wire ropes for holding the brick-work together.

w represents soil or other suitable material covering the arches in order to keep in heat while the chambers are being fired, and it also forms a floor on which to walk, or on which goods can be dried before they are burned, in which case I cover the whole with a roof.

When only one of the sets or ranges of chambers is used, the fire and heated gases, after arriving at the last chamber *a*, or that nearest to the chimney *l*, can be allowed to escape directly into the flue *k*; or they may be caused to return back along the underneath flues, *j*, and heat the first chamber of the range by closing the damper *e'* and unstopping the nearest opening *i*, the next adjoining opening *i'* being built up, when the fire and heated gases will descend into the underneath flues, *j*, and proceed back toward the most distant opening *i* from the chimney, up which they will ascend and circulate around and heat or help to heat the chamber *a* farthest from the chimney.

In practice the front and back fire-holes *e* are first fired until the outer flue *c* of the first chamber *a* is heated sufficiently, when the first of the side fire-holes *e* is fired, the flame and gases circulating along the lateral flues *c*, around as many of the parallel chambers *a* as may be required to be warmed and heated, when they are allowed to escape down one or more of the openings *i* into the underneath flues, *j*, whence they are drawn to the chimney *l*. When the materials in the first chamber *a* are sufficiently baked or burned, the front or back fire-holes *e* and the first end fire-hole *e* are closed up and the fire-bars sanded down, so that no more cold air can enter than is required to cool the chamber quickly or slowly, according to the nature of its contents.

The same process is observed with the second chamber when the goods therein have become sufficiently baked or burned. As fast as the goods in the back chambers are sufficiently burned and the fire-holes closed and bars dampered down, other fire-holes *e* toward the chimney *l* are opened and commenced to be fired along the ranges, the dampers *m*, covering the openings *i*, being regulated so as to cause the goods in the chambers to be heated, burned, and cooled in steady succession, as required, it being possible to

regulate the speed of the different operations with the greatest nicety.

The drawings show a double range of only five chambers each; but it is evident that a large number may be employed by the addition of chimneys at intervals to assist the draft for the fires.

The horizontal openings a^3 , Figs. 3 and 5, are shown open; but in the process of drawing, setting, and burning it is evident that some of them are stopped up when and where it is required to prevent the fire, gases, and cold air from passing through. This is carried out as the work proceeds by building them up with loose bricks and daubing over.

In this system of parallel chambers the heat is economized in several ways. After burning the contents of one or more chambers it proceeds forward toward the opening or openings i , down which it is drawn successively and gradually, heating the chambers and drying and heating the contents, and at the same time allowing steam to escape, so as to prevent bursting or discoloration by the too rapid accumulation of steam in the chambers; also the heat from the chambers that have been fired is carried forward and assists in heating the chambers that are being fired, and economy is thus effected. The chambers also expose comparatively little external surface, which would allow of the heat radiating away and being of no service. The sides of the lateral flues (with the exception of the two end chambers) being made of thin fire-bricks, the heat radiates on both sides into the chambers and among the contents to be burned, instead of being absorbed into "thick side walls," or radiating into the open air on one side, as is generally the case in muffled kilns or ovens. The length of the chambers allows the heat to be absorbed with economy and regularity, and their narrowness not only allows the heat to penetrate quickly through the contents, but the con-

tents do not in consequence suffer from contraction, as is the case in wide chambers set and burned in the usual manner.

The wickets can all be built up with loose bricks and daubed over for removing easily, or one end of the chambers can be built up for a permanency, and one end only removed for the purpose of setting and drawing the contents.

Instead of arching over the chambers a , I sometimes set the top course of bricks or other material to be burned in close order and daub over their top, putting soil or other material over that to keep the heat from radiating while being fired and the contents from suffering from the weather before being fired.

It will be evident that a combination of the herein-described arrangements of muffle fire-chambers can be used with open fire-chambers, the lateral flues being employed for the purposes of drying the contents of the chambers. When the contents are dry, the ends of the flues are stopped up, and the fire and heated gases pass through and among the contents. By this arrangement the contents are more thoroughly protected from discoloration and cracking in the process.

Having now particularly described and ascertained the nature of my said invention and in what manner the same is to be performed, I declare that what I claim is—

An oven or kiln for burning bricks in which the chambers are muffled or closed, provided with the flues a' , lateral flues $c c$, underneath flues, j , and the flues k , leading to the chimney and having front and back doors or wickets, $g h$, with holes $r r$ therein for expelling the steam in the process of drying, all substantially as set forth.

R. STANLEY.
